(57) **CLAIM**

We claim the ornamental design for a model vehicle roof skid, as shown and described.

DESCRIPTION

FIG. 1 is an upper, left, front perspective view of a model vehicle roof skid showing our new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is an upper plan view thereof;

FIG. 7 is a bottom plan view thereof; and,

FIG. 8 is an upper, left, front perspective environmental use view of the model vehicle roof skid.

In the drawings, the broken lines illustrate portions of the model vehicle roof skid that form no part of the claimed design; whereas, the broken line showing of the environmental use view depicts environmental subject matter and is provided for the purposes of illustrating environmental use structure and context and also forms no part of the claimed design.
